(57) **CLAIM**

We claim the ornamental design for a preform for dosing bottle, as shown and described.

DESCRIPTION

FIG. 1 is a top, front perspective view of a preform for dosing bottle, showing our new design and shown in a partially inverted orientation;

FIG. 2 is a front elevational view of the preform for dosing bottle in FIG. 1, shown in an upright orientation;

FIG. 3 top plan view thereof; and,

FIG. 4 bottom plan view thereof.

The broken lines shown in the drawing views are included for the purpose of showing environmental structure that forms no part of the claimed design.
